2 SHEETS—SHEET 2.

UNITED STATES PATENT OFFICE.

JOSEPH KOMANCSEK, OF ASTORIA, NEW YORK.

DEVICE FOR TRIMMING LINOTYPE-SLUGS.

1,106,948.

Specification of Letters Patent. Patented Aug. 11, 1914.

Application filed December 22, 1913. Serial No. 808,091.

To all whom it may concern:

Be it known that I, JOSEPH KOMANCSEK, a citizen of the United States, residing in Astoria, in the county of Queens, in the 5 State of New York, have invented certain new and useful Improvements in Devices for Trimming Linotype-Slugs, of which the following is a specification, reference being had to the accompanying drawings, forming 10 a part hereof.

This invention relates to devices for trimming the side faces of linotype or printing slugs as they are ejected from the mold in which they are cast.

15 In linotype machines it is the common practice to pass the cast slugs between trimming knives, one of which is fixed and the other of which is relatively adjustable to determine the thickness of the body of the 20 type.

This invention is concerned particularly with the improvement of the means for adjusting such a trimming knife and with the devices for locking the same in adjusted 25 position.

Hitherto, the adjustment of the movable knife has been effected by means of a series 30 of stepped shoulders coöperating with the guide for said knife and acting in opposition to suitable springs which tended to separate the knives. In such known machines the means for locking the adjustable knife and the adjusting devices in operative 35 position have not been entirely satisfactory in that they permit a slight relative movement of the adjusting devices which relative movement is often sufficient to make the slug of some other than the standard thickness.

40 It is the object of this invention to provide trimming knives and adjusting and locking devices therefor which shall be more effective in their operation than corresponding devices now generally in use and shall 45 embody in their construction and arrangement fewer disturbing factors than formerly, by which the chances for inaccuracy in the thickness of the type are diminished, and which coöperate in such a manner as 50 to eliminate the injurious wear on the parts to which previous machines are subjected. In accordance with the invention springs are eliminated in so far as the trimming knives and their adjusting and locking devices are 55 concerned and provision is made for the positive adjustment of the movable knife

and the clamping thereof in its certain adjusted position. The relatively movable parts of the devices are relieved, in so far as possible, from frictional engagement with each other whereby they would be subjected to wear and consequent loss in accuracy and such parts are relieved from strains to remove their liability to derangement or movement from their proper positions. In addition to making such general improvements as have been referred to herein this invention also seeks to provide devices which shall permit a greater range of adjustment of the thickness of the slug than has hitherto been possible and facilitate the interchanging of the gage plugs by which intermediate thicknesses of the slugs may be more readily secured than hitherto.

Still another object of the invention is to 75 provide improved means coöperating with the knives to prevent the slug from being thrown too far through the knives and to guide the slug in its travel.

Reference is now to be had to the accompanying drawings for a detailed description 80 of the invention, in which—

Figure 1 is a view in front elevation of the improved trimming device showing it in the position which it will assume when attached to the standard linotype machine. Fig. 2 is a sectional view taken on the plane indicated by the line 2—2 of Fig. 1 and looking in the direction of the arrows. Fig. 3 is a view in elevation of the device shown 90 in Fig. 1, looking at one of the side faces thereof. Fig. 4 is a view similar to Fig. 3, but looking at the other side face of the trimming device. Fig. 5 is a sectional view, on a somewhat larger scale, showing a portion of the supporting frame, the eccentric 95 for adjusting the slide and the gib and its clamping bolts. Fig. 6 is a view in perspective of the gib for locking the slide in adjusted position. Fig. 7 is a conventional 100 showing of one of the gage plugs and the locking pin therefor.

The frame *a* is provided with a partly circular flange *a'* formed with an opening *a*² to permit access to the cylindrical drum *b* which is secured to a rotatable shaft *c* provided with a milled knob *c'* to facilitate manual rotation and with a graduated dial *c*² for registration with an index or pointer *a*³ on a cover plate *a*⁴ secured to the flange *a'* or housing *a'*. In the front wall of the frame *a* is mounted a reciprocable knife

slide d , to the edge of which is adjustably secured a knife e , as by screws d' , the co-operating fixed knife being indicated conventionally as at E . The screws d' preferably pass through elongated apertures formed in the body of the knife, as usual, to permit an initial adjustment of the knife with respect to the slide d to insure parallelism of the knife edge to the co-operating fixed knife edge, and to secure this adjustment in the present embodiment there are shown brackets d^2 formed on the face of the slide d and through which pass adjusting screws f and locking bolts g to permit the knife to be locked in its adjusted position with respect to the slide. As indicated in Figs. 1 and 5, the side of the slide d is recessed to receive an eccentric h carried on the end of a rod h' to which is affixed a convenient handle h^2 to facilitate manual oscillation of the eccentric h for the purpose of moving the slide d with respect to the frame a so that an adjustment of the knife e with respect to the co-operating fixed knife E is secured. The extent of such movement of the slide d under the influence of the eccentric h is determined by devices now to be described.

In the outer face of the slide d is mounted, preferably removably, a stud l while through the cover plate a^4 of the housing a' is passed a threaded stud or anvil l which is in alignment with the first named stud l . Between these two studs l and l may be positioned by rotation of the drum b , any one of a series of gage plugs m which are successively of increasing lengths and are arranged in the drum to form an annular series concentric therewith. Each of these gage plugs m may be milled intermediate its ends, as at m' , to receive a locking pin n passed inwardly from the edge of the drum and adapted to hold the plug within the drum while permitting through the milled portion a limited axial movement thereof for reasons which will be pointed out hereinafter. As viewed in Fig. 2, the pin n is slightly in perspective, although it will be evident that it is between the upper and lower shoulders of the recess m' and within the latter, the bottom of the recess being formed on a chord of the circular pin m . The graduated dial c^2 integral with the milled knob c' , it will be understood, is graduated according to the effective lengths of the gage plugs m when positioned between the anvil l and the stud l for the purpose of making it possible to determine the distance between the adjustable knife e and the fixed knife E and accordingly the thickness of the slugs. Step-by-step rotation of the drum b to bring any one of the gage plugs m in exact alignment with the studs l and l , in the manner described, may be assured by a spring-pressed ball detent o car-

ried on the inner face of the cover plate a^4 and co-operating with a series of depressions formed on the upper face of the drum.

In effecting an adjustment of the movable knife e , the locking devices hereinafter to be described being in inoperative position, the drum b is rotated by the operator until the dial c^2 indicates that the proper gage plug m for the thickness of the slugs desired is in alignment with the anvil l and the stud l . The operator then oscillates the eccentric h by means of the handle h^2 so as to move the slide d and press the gage plug m firmly between the anvil l and the adjusting stud l . In this position, it will be evident that the length of the particular gage plug which is in position between the studs l and l will determine the distance between the adjustable knife e and the co-operating fixed knife E .

In practice, of course, it is necessary to provide suitable devices for locking the adjustable knife slide in its adjusted position and with these locking devices this invention is also concerned. Referring to Fig. 5, it appears that the slide d has one edge disposed in an undercut way a^5 within the frame a , while the opposite edge is also in engagement with a suitable beveled gib p disposed between a portion of the frame a and the beveled edge of the slide d . The gib p has in threaded engagement therewith a suitable rod q which is journaled in the frame a and is provided with an operating handle q' by which the gib p may either be drawn inwardly to clamp the slide d or may be released from its engagement therewith to permit the slide to be reciprocated in its ways. When the gib p is drawn inwardly by manual rotation of the threaded rod q through the handle q' it will be observed that the slide d is forced upwardly, as viewed in Fig. 5, into the undercut way a^5 and at the same time has its inner face forced into snug engagement with the contacting front face of the frame a . To facilitate the release of the gib p from this locking engagement a suitable spiral spring r is interposed operatively between the frame a and the gib p .

From the description given of the operation of the adjusting devices and of the construction of the locking means, it will now be evident that when the adjusting devices are to be manipulated it is first necessary for the operator to rotate the threaded stud q so as to release the gib p from its locking engagement with the slide d , whereupon the latter may be moved in its ways by means of the eccentric h so as to permit the drum b to be rotated until the proper gage plug m is positioned in alignment with the anvil l and stud l , at which time the eccentric is again operated to move the slide d to press the gage plug m between the studs l and l ,

thus preventing positively further movement of the slide. When this adjustment is effected the rod *q* is then rotated to force the gib *p* against the action of the spring *r* 5 into locking engagement with the slide *d*. During rotation of the drum *b* it is to be observed particularly that none of the gage plugs *m* is in frictional engagement with either of the studs *k* or *l* or with any other 10 member and that the only wear to which said plugs are subjected is such as comes from direct axial compression thereof and such wear has been found to be negligible. Furthermore, the disposition of the gib *p* 15 and its coöperation with the slide *d* and frame *a* are such that the knife *e* is locked with certainty in its adjusted position and absolutely no lateral movement thereof through any of the adjusting factors is permitted. The two characteristics just noted 20 are those which above all others have made previous devices of the same general type inaccurate in their operation and liable to constantly changing elements of error, and 25 it is the features of construction described herein which obviate such inaccuracies in the improved machine. It is to be noted further that the opening *a*² in the wall of the housing *a*' permits ready access to be had to 30 the gage plugs *m* and that by the removal of the retaining pin *n* any one of said gage plugs may be removed and have substituted therefor very readily a new plug or a plug of different length to permit intermediate 35 thicknesses of type to be secured.

Another feature of the present invention resides in the provision of improved means for preventing the type from being thrown too far through the cutting knives, and in 40 the illustrated embodiment such means consist of a plate *s* which has its forward edge reversely curved, as at *s'*, and seated within a corresponding curved recess formed in the rear face of the adjustable knife *e*. The 45 plate is held hingedly with the reversely curved forward edge *s'* seated in the recess of the movable knife by a flat plate *t* secured to the rear face of said knife and projecting downwardly over said reversely curved portion 50 of the plate *s* and bearing against said portion to hold it in its seat in the recess of the knife. The plate *s* stands normally inclined across the path of the slugs as they are forced between the knives and it is held 55 yieldingly in this position by means of a flat spring *u* positioned on the lower edge of the slide *d*. As the slug passes between the trimming knives its progress is checked by the plate *s* moving about the hinged joint 60 formed by the portion *s'* in the recess, against the action of the spring *u* and the slug is thereby prevented from being thrown through. When the movable knife *e* is adjusted, it will be observed that the plate *s* 65 moves therewith, and the novel means of at-

taching said plate hingedly to said knife eliminates the likelihood of sticking, a fault which has generally been present in previous slides.

The improved device is not to be limited 70 in its application to any particular type of machines but will be useful under any circumstances in which the thickness of cast slugs is to be accurately determined. Nor is the invention to be limited to the particular embodiment illustrated in the accompanying drawings as corresponding results may be obtained by those skilled in the art by means of well known mechanical equivalents substituted in place of the parts described. 75 80

I claim as my invention:

1. In an attachment of a linotype machine for trimming slugs, the combination of a fixed knife, a frame, knife slide mounted movably therein, a fixed plate, a rotatable drum mounted operatively between said plate and the slide and a series of gage plugs carried loosely in said drum and movable respectively to an operative position between the plate and the slide to constitute an abutment therebetween and limit the movement of the slide in one direction. 90

2. In an attachment of a linotype machine for trimming slugs, the combination of a fixed knife, a frame, a knife slide mounted movably therein, a fixed plate, a rotatable drum mounted operatively between said plate and the slide, a series of gage plugs carried loosely in said drum and movable respectively to an operative position between the plate and the slide to constitute an abutment therebetween and an eccentric in operative engagement with the slide to move the same positively into engagement with the gage plugs. 95

3. In an attachment of a linotype machine for trimming slugs, a fixed knife, a movable knife, a series of gage plugs to permit the adjustment thereof and a rotatable drum in which the plugs are carried loosely and threaded pins to secure said plugs within the drum, each plug being provided with a milled recess intermediate its ends within which the threaded pin rests to permit axial movement of the plug. 110

4. In an attachment of a linotype machine for trimming slugs, the combination of a fixed knife, a frame, a knife slide mounted adjustably therein, an eccentric in direct engagement with said slide to move the same positively, a shaft journaled in the frame, a drum affixed to said shaft, a circular series of gage plugs mounted loosely within the drum, a housing for said drum, a top plate for the housing provided with an index and an independent dial mounted on said shaft and adapted to coöperate with said index to indicate the position of said slide. 120 125

5. In an attachment of a linotype machine for trimming slugs, the combination of a 130

fixed knife, a frame, a knife slide mounted movably therein and bearing directly along one edge against the frame, means to adjust the knife slide, a gib disposed operatively 5 between the frame and the other edge and means disposed in juxtaposition to the adjusting means for the knife slide for setting up the gib to draw the face of the knife slide against the proximate face of the frame and 10 thereby lock the slide in the frame.

6. In an attachment of a linotype machine for trimming slugs, the combination of a fixed knife, a frame, a knife slide mounted 15 adjustably therein and having one edge resting in an undercut way formed in the frame, means to adjust the knife slide, a beveled gib interposed between the frame and the other beveled edge of the slide and means disposed in juxtaposition to the adjusting means for 20 the knife slide to set up the gib to force the slide firmly against the undercut way and simultaneously draw the slide against the face of the frame to lock the slide against movement, said means permitting the release of the gib. 25

7. In an attachment of a linotype machine for trimming slugs, the combination of a fixed knife, a frame, a knife slide mounted 25 adjustably therein and having one edge

resting in an undercut way formed in the frame, manual means to adjust the knife slide, clamping devices including a beveled gib interposed between the frame and the other beveled edge of the slide, manual means disposed in juxtaposition to the adjusting means for the knife slide to set up the gib to force the slide firmly against the undercut way and simultaneously draw the slide against the proximate face of the frame to lock the slide against movement, 40 and a spring to retract the gib upon the release of the clamping devices.

8. In a linotype machine, the combination of a frame, a knife slide adjustably mounted therein, a knife carried by the slide, a fixed knife, a stop plate having one edge reversely curved, a correspondingly curved recess in the adjustable knife in which the plate is hingedly secured and a spring carried on the slide and in operative 50 engagement with the plate.

This specification signed and witnessed this nineteenth day of December A. D. 1913.

JOSEPH KOMANCSEK.
